[57] CLAIM

The ornamental design for an elevated toilet seat, as shown and described.

DESCRIPTION

FIG. 1 is a front elevation of a toilet seat embodying my new design;

FIG. 2 is a rear elevation thereof;

FIG. 3 is a top plan view thereof;

FIG. 4 is a left side elevation thereof, the right side being a mirror image of the left side shown; and

FIG. 5 is a bottom plan view thereof.

FIG. 1.

FIG. 2.

FIG. 3.

FIG. 4.

FIG. 5.
